UNITED STATES PATENT OFFICE.

PERCY E. GOODWIN, OF EVANSVILLE, INDIANA, ASSIGNOR TO THE STEEL SCAFFOLDING COMPANY, OF EVANSVILLE, INDIANA, A CORPORATION OF INDIANA.

MORTAR-BOARD ADJUSTABLE AND FOLDABLE STAND.

Application filed August 3, 1927. Serial No. 210,316.

My invention relates to an improved metal stand adapted for holding the mortar board used by a plasterer, mason, or other artisan.

Heretofore, mortar board stands have ordinarily been made of wood and of two different heights, namely about eighteen, and about thirty inches high, one or the other height being used according to the height of the artisan, because it has been found that a most convenient height for the support of a mortar board is at about the waist line.

However, the two sizes in which the ordinary mortar board stand has heretofore been made, do not allow for adjustability to heights a few inches above or a few inches below the above-named dimensions and, hence, they have not afforded a support at the height found by the particular artisan to be most comfortable and convenient for his work.

The object of my invention is to provide an improved mortar board stand of metal, preferably mainly of angle iron bars for the purpose of lightness and strength, which will provide means whereby the effective height of the stand may be changed within a range of several inches above and below the usual eighteen and thirty inch heights which have become more or less standard, thereby enabling the artisan to use a stand of the height which he desires, according to his stature, with adaptability for adjustment up or down within a range of several inches so that he can have the stand at a height which he finds best suited for his work.

My improved stand is of that general type embodying pairs of crossed legs pivoted together, combined with novel means for adjusting the pairs of legs to vary the height of the parts which connect the legs and are intended to support the mortar board.

I have found that a pair of chains adjustably connecting the respective pairs of legs and, preferably, attached to the bars to which the legs are secured, constitute a satisfactory, conveniently adjusted, and durable means for this purpose. With an adjustable connection of this character, one end of each chain may be suitably connected to one cross piece and a hook may be provided on the other cross piece for engagement with any link of the chain, in each instance.

Not only does this provide a strong, durable, and easily adjusted connection, but the chains naturally and readily drop down or

fold when the legs and their cross pieces are folded.

For the purpose of bracing the cross pieces from the legs, strap braces are provided. These braces serve the further purpose of confining the folded chain between them when the stand is folded, so that the chain cannot sway or swing out of position when the stand is folded and is being moved from place to place; hence, the stand may be folded into compact arrangement for carriage or storage.

A practical embodiment of the invention is set forth hereinafter, recited in the appended claims, and shown in the accompanying drawings, in which:

Figure 1, is a perspective view, showing the stand extended, ready for use;

Fig. 2, is an elevation, the stand being folded; and

Fig. 3, is a detail perspective view showing one of the hooks and an end of a chain.

The stand comprises two frames which are substantial duplicates, and two adjustable chains which connect the cross pieces of the frames in the general region of the ends thereof so that the tensioning effect is equalized and twisting or distortion of the frames under the weight of the mortar board and its contents are prevented; furthermore, there is an improved relationship between the respective chains and the braces for the frames to enable the chains to be confined when the frames are folded.

The frames each comprise legs 1, preferably of angle iron for the purpose of lightness and strength, the lower ends of the legs being provided with feet 2 to form a suitable support for the legs when the stand is in use, these feet being formed by bending up the end of one of the flanges of the leg and welding it to the other flange thereof.

A cross piece 3 connects each pair of legs. Preferably, this cross piece is of angle iron to afford the requisite rigidity and strength so that buckling will be prevented.

Metal straps 4 connect one flange of the cross piece 3 to the under flanges of the legs 1. These straps are preferably of flat stock. Connections for the cross piece and the straps are preferably rivets 5 so that the bars are permanently connected together.

The pairs of legs 1 of the two frames are pivoted together at 6, such pivots preferably being rivets with interposed washers (not

shown) to minimize friction. These pivots 6 enable the legs to be spread out in cross relationship when the stand is in use or is not folded and they also permit the frames to be 5 folded together.

My improved adjustable connections between the cross bars 3 and the frames consist of chains 7 connected by links 8 to one of the cross bars and adjustably connected to the remaining cross bar by hooks 9 carried by said 10 bar.

As previously explained, ordinary practice has dictated that mortar board stands are of a most convenient height when eighteen 15 inches or thirty inches high.

Following this practice, my improved stand will preferably be so constructed and proportioned that it may be made in either of these sizes but with the added advantage, 20 not possessed by the old style of stand, namely adaptability for adjustment within a range of a few inches above or below these heights and herein resides the adaptability of the stand to be varied in height to exactly suit 25 the requirements of the artisan who is using it, whether he be short, of medium height, or tall. By letting out the chains or taking them up and engaging another link of each 30 of them with its respective hook, the proper adjustment may be obtained. By disposing the chains in the general regions of the ends of the cross bars 3, there is an equalization 35 of the tension so that any twisting or bending or unevenness of the stand is prevented. 40 Another advantage inhering in this position of the chains is that when the stand is folded, the chains naturally loop or fall between the braces. Preferably, the braces connecting 45 the legs of one frame to the cross bar thereof are arranged so that they are in off-set relation to the braces connecting the legs to the cross bar of the other frame, which affords a much wider surface to engage the chains when the latter are folded and thus the better 50 retains the chains against displacement.

when the stand is folded for storage or carriage.

It will be seen from Fig. 2 that when the stand is folded, there is a substantial alignment of all of the legs and that the cross 55 bars are located side by side with the looped or folded chains depending from them and lying between the braces; consequently, the stand occupies very little space and can be conveniently stored or carted or numbers of 55 the stands stacked, if it is desired to move them in considerable quantities, thus minimizing the amount of space required.

What I claim is:

1. In an adjustable and foldable stand, 60 the combination of frames, each frame comprising a pair of legs, a cross bar, and means for bracing the frames, the legs of one frame being pivoted to those of the other frame so that the frames may be folded together, and 65 a pair of independent foldable and adjustable connections attached to the cross bars at points which are located on opposite sides of the central parts of the aforesaid cross 70 bars, said connections being adapted to span the space between the frames when the stand is set up, for the purpose of equalizing the tensioning effect and to prevent twisting or distortion of the frames when the stand is 75 in use.

2. In an adjustable and foldable stand, the combination of frames, each comprising a pair of legs and a cross bar, the legs of one frame being pivoted to those of the other frame so that the frames may be folded together, braces connecting the legs and the cross bar of each frame, and independent foldable connections attached to the respective cross bars between the points of connection of the legs and braces thereto and which 80 will be positioned between, and be confined by, the braces of the respective frames when the frames are folded together.

In testimony whereof I affix my signature.

PERCY E. GOODWIN.
